BURTON SMITH, OF GRANTS PASS, OREGON

JOINT CONNECTION

Application filed January 19, 1929. Serial No. 333,671.

This invention appertains to improvements in joint connections generally, and more particularly to a slip-on type of such connections for uniting the adjacent ends of flume sections and the like.

An object of the invention is to provide a device of the class set forth, which is of an extremely simplified, but durable and efficient construction and arrangement of parts, 10 comparatively inexpensive to manufacture, and readily and easily installed in position. Another object of the invention is to provide a joint connection as hereinbefore characterized, which is to be made from a single 15 piece of sheet metal folded upon itself in a manner to effectively join adjacent flume or trough sections together without danger of leakage at a completed joint, and which, when properly installed, requires no support 20 other than the connected ends of the said sections.

A further object of the invention is to provide a means which will cooperate with the improved joint connection in a manner to effectively brace and otherwise reinforce a flume or trough in a manner to prevent 25 spreading of the side walls thereof.

Another object of the invention is to provide a joint of the character mentioned, 30 which will allow for a greatly increased amount of expansion and contraction to the parts of a completed flume or trough, without in any way affecting the efficiency of the joints thereof in preventing leakage therefrom.

With the foregoing and other equally important objects and advantages in view, the invention resides in the certain new and useful combination, construction and arrangement of parts as will be hereinafter more 40 fully described, set forth in the appended claims, and illustrated in the accompanying drawings, in which:

Figure 1 is a fragmentary side elevation, 45 partly in section, showing two of the completed joints in accordance with a preferred embodiment of the present invention,

Figure 2 is a similar view, but showing the joints in a slightly modified form,

50 Figure 3 is a vertical transverse section

taken on the line 3—3 of Figure 1,

Figure 4 is a perspective view of an assembly of one of the preferred forms of the joints, and the adjacent end joint of a flume or trough section to be engaged therewith, 55 and

Figure 5 is a perspective view of a blank from which a joint connection is to be formed.

Referring to the drawings, wherein like 60 characters of reference designate corresponding parts throughout the several views thereof, and more particularly to Figures 1, 3, 4 and 5, the embodiment of the invention, as shown therein by way of 65 example, comprises generally a blank of sheet metal adapted to be folded upon itself on parallel longitudinal lines designated 10, 11, 12 and 13 to provide an upper portion 14, an intermediate portion, and a lower 70 portion 16, when folded. In this particular form of the joint connection, however, a flange 17, at the outer side of the line of fold 13 and of substantially equal length to that of the intermediate portion 15, is bent 75 upwardly and over onto the upper side of the adjacent lower portion 16 to form a solid bead along the free edge of the latter to strengthen the same, and to otherwise increase the grip of this portion of the joint 80 connection with the lower side of the end of the flume or trough section to be engaged between the same and the intermediate portion 15. Similarly, a flange 18, also of a 85 length equal to that of the intermediate portion 15, and consequently to that of the flange 17, at the outer side of the line of fold 10, will be folded under the adjacent portion of the upper portion 14 to form a 90 solid bead along the free edge of the latter to add strength thereto, and to increase its gripping effect on the upper or inner side 95 of the end of the flume or trough section complementary thereto. The opposite ends of the upper and lower portions 14 and 16 are extended beyond the complementary ends of the intermediate folded portion 15 and the bead flanges 17 and 18, with the end portion 19 of the upper folded portion 14 100

101

made slightly longer than the similar portion 20 of the lower folded portion 16.

With the blank folded in the manner above indicated for the same, it will now be bent to the form of the arc defined by the curvature of the adjacent ends of the flume or trough sections *a*, which are to be engaged between the folds of the portions 14, 15 and 16, and thereafter these ends of the flume or trough sections *a* will be so engaged to establish the end of one of the sections *a* between the upper folded portion 14 and the intermediate folded portion 15, and the end of the other of the sections *a* between the latter folded portion 15 and the lower folded portion 16. The opposite ends of the flume or trough sections *a* are, however, preferably angularly bent, as at 21, to form shoulders which are abutted by the solid beads formed by the folded flanges 17 and 18 on the upper folded portion 14 and the lower folded portion 16 in a manner to further assure that no leakage will occur through the joint connection.

Where the flume or trough sections *a* are formed with oppositely disposed and angularly arranged side flanges *b*, and after the adjacent ends of a pair of the sections have been engaged with a joint connection in accordance with the present invention, the extensions or tongues 19 and 20 at the opposite ends of the latter will be bent over onto these flanges *b*, and one upon the other, when securing bolts or the like 22 will be passed through aligned openings 23 in these parts to rigidly fasten the same together, and to otherwise make the flume or trough a substantially unitary structure, when completed.

The flume or trough structure, and particularly the joints thereof may be strengthened and otherwise prevented from separating by the employment of cross bars or braces 24 therewith, which are preferably in the form of elongated strips of sheet metal of inverted channel form, having the opposite side flanges thereof cut away inwardly from the opposite ends of the same to provide tongue portions 25, which are bent over the upper extensions or tongues 19 and 20 of the joint connections, and abut the outer sides and the lower edges of the angular flanges *b* formed at the opposite sides of the flume or trough sections *a*. These tongue portions 25 are preferably apertured for engagement by the fastenings 22 aforesaid. It is to be noted that the openings 23', formed in the flume or trough section end are preferably of elliptical or oval form to allow for a necessary amount of expansion or contraction in the same and the joint connection.

As shown in Figure 2, the joint connection depicted therein is formed from a blank 35 with the bead forming flanges 17 and 18

eliminated therefrom, so that the upper, intermediate and lower folded portions 14', 15' and 16' closely engage the opposite sides of the engaged ends of the flume or trough sections *a*, and, as a result of this arrangement, the shoulders 21 of the latter, as employed in the first instance of the invention, are dispensed with.

In this latter form of the invention, and in the case of the flume or trough sections *a*' not being normally provided with oppositely disposed and angularly arranged side flanges, similar flanged portions *b*' are preferably bent out from the opposite edges of said sections, so that the opposite extensions or tongues 19' and 20' of the joint connection may be bent over these flanged portions, and secured thereby by means of the bolt fastenings 22'.

Without further description, it is thought that the features and advantages of the invention will be readily apparent to those skilled in the art, and it will of course be understood that changes in the form, proportion and minor details of construction may be resorted to, without departing from the spirit of the invention or the scope as claimed.

Having thus fully described the invention, what is claimed is:

1. A slip-on joint connection for sections of a flume or other trough-like structure comprising a blank of sheet metal folded upon itself to form an upper portion, an intermediate portion and a lower portion between which the opposed ends of the adjacent of the said sections are to be engaged, the free longitudinal side edges of the said upper and lower portions being extended beyond the lines of fold of these portions with respect to the said intermediate portion, the outer portions of the said extended free edges being infolded to form solid beads adapted to bear against the adjacent walls of the engaged ends of the said sections.

2. A slip-on joint connection for sections of a flume or other trough-like structure comprising a blank of sheet metal folded upon itself to form an upper portion, an intermediate portion and a lower portion between which the opposed ends of the adjacent of the said sections are to be engaged, the free longitudinal side edges of the said upper of these portions with respect to the said intermediate portions, the opposite ends of the said upper and lower portions being extended to provide tongue portions adapted to be bent over the adjacent side edges of the engaged ends of said sections whereby to increase the gripping action of the said folded portions on the latter, and means for securing said tongue portions and said sections together.

3. A slip-on joint connection for sections

of a flume or other trough-like structure comprising a blank of sheet metal folded upon itself to form an upper portion, an intermediate portion and a lower portion between which the opposed ends of the adjacent of the said sections are to be engaged, the free longitudinal side edges of the said upper and lower portions being extended beyond the lines of fold of these portions with respect to the said intermediate portion, the outer portions of the said extended free edges being infolded to form solid beads adapted to bear against the adjacent walls of the engaged ends of the said sections, the opposite ends of the said upper and lower portions being extended to provide tongue portions adapted to be bent over the adjacent side edges of the engaged ends of the engaged ends of said sections.

4. A slip-on joint connection for sections of a flume or other trough-like structure comprising a blank of sheet metal folded upon itself to form an upper portion, an intermediate portion and a lower portion between which the opposed ends of the adjacent of the said sections are to be engaged, the free longitudinal side edges of the said upper and lower portions being extended beyond the lines of fold of these portions with respect to the said intermediate portion, the outer portions of the said extended free edges being infolded to form solid beads adapted to bear against the adjacent walls of the engaged ends of the said sections, the opposite ends of the said upper and lower portions being extended to provide tongue portions adapted to be bent over the adjacent side edges of the engaged ends of said sections, and means for securing said tongue portions together.

5. A slip-on joint connection for sections of a flume or other trough-like structure comprising a blank of sheet metal folded upon itself to form an upper portion, an intermediate portion and a lower portion between which the opposed ends of the adjacent of the said sections are to be engaged, the free longitudinal side edges of the said upper and lower portions being extended beyond the lines of fold of these portions with respect to the said intermediate portion, the outer portions of the said extended free edges being infolded to form solid beads adapted to bear against the adjacent walls of the engaged ends of the said sections, the opposite ends of the said upper and lower portions being extended to provide tongue portions adapted to be bent over the adjacent side edges of the engaged ends of said sections, and means for securing said tongue portions and said sections together.

Signed at Grants Pass in the county of Josephine and State of Oregon this 10th day of December A. D., 1928.
